FIREPLACE

Arthur Pulos, 201 Churchill Lane, Fayetteville, N.Y.

Filed Oct. 20, 1965, Ser. No. 88,256

Term of patent 14 years

(Cl. D81—7)

FIG. 1

FIG. 2

FIG. 4

FIG. 3

The broken line showing of a flue in FIGS. 2, 3 and 4 is for illustrative purposes only.

I claim:

The ornamental design for a fireplace, as shown and described.
